UNITED STATES PATENT OFFICE.

FRANK CHAPMAN, OF WINAMAC, INDIANA, ASSIGNOR OF ONE-FOURTH TO SYLVESTER CHAPMAN, AND ONE-FOURTH TO WILBERT CHAPMAN, BOTH OF WINAMAC, INDIANA.

WATER MOTOR.

Application filed May 29, 1922. Serial No. 564,409.

To all whom it may concern:

Be it known that I, FRANK CHAPMAN, a citizen of the United States, residing at Winamac, in the county of Pulaski and 5 State of Indiana, have invented certain new and useful Improvements in Water Motors; and I do hereby declare the following to be a full, clear, and exact description of the invention, such as will enable others skilled 10 in the art to which it appertains to make and use the same.

The present invention relates to water motors, and aims to provide a novel and improved over-shot submerged device for 15 obtaining power from the water flowing over it.

Another object is the provision of a water motor of that kind having buoyant blades which, on account of their buoyancy, will 20 automatically move to extended or open and folded or closed positions when moving with and against the current.

With the foregoing and other objects in view, which will be apparent as the description 25 proceeds, the invention resides in the construction and arrangement of parts, as hereinafter described and claimed, it being understood that changes can be made within the scope of what is claimed, without 30 departing from the spirit of the invention.

The invention is illustrated in the accompanying drawings, wherein—

Figure 1 is a plan view of the improved water motor.

Fig. 2 is a side elevation thereof, portions being shown in section.

In carrying out the invention, there is provided a rectangular frame 7 of suitable size and composed of wood, metal or other 40 suitable material, which frame is located between a pair of front piers 8 and a pair of rear piers 9, said piers being located at the corners of the frame. The frame is mounted for vertical adjustment, and the piers, which are of concrete, have the plates 45 10 along which the front and rear ends of the frame can slide upwardly and downwardly, the rear end of the frame preferably having rollers 11 to bear against the rear piers for reducing the friction when moving 50 the frame upwardly or downwardly. Vertical screws 12 are swivelled at their lower ends to the corner portions of the frame, as at 13, and are threaded upwardly through 55 overhanging brackets 14 secured on the

upper ends of the piers, and said screws can be turned by handles or wrenches engaging the upper terminals thereof, for adjusting the frame to the desired vertical position.

The water motor proper is carried by the 60 frame 7, and includes the front and rear transverse shafts 15 and 16, respectively, journaled in the frame, and having sprocket wheels 17 secured thereon at spaced transverse positions, and endless sprocket chains 65 18 pass around said sprocket wheels. The chains are arranged in pairs, and there may be any suitable number of such chains, according to the width of the motor. The frame has a deck 19 on which the upper 70 runs of the chains are supported, and said deck can be firmly supported by bracing or lattice work, as seen in Fig. 2. The blades 20 are hingedly connected to the chains and are arranged transversely of the chains to 75 swing away from the chains in the direction of travel of the chains to open or extended position, and said blades swing away from the direction of travel of the chains against the chains to folded or closed position. Chains 21 or other flexible elements are connected to the blades and to the chains 18 for limiting the opening movement of the blades, and said blades are preferably 80 of sheet metal and hollow so as to be buoyant, although they may be rendered buoyant 85 in other suitable manners.

In order to reduce the flow of water under the motor, the lower portion of the frame is boxed in, as at 22, in order to 90 avoid, as much as possible, counter pressure against the lower runs of the chains. A curved shield 23 also preferably extends around the front end of the motor, and may have overhanging arms 23' extending over the spaces between the pairs of front sprocket wheels. The blades in moving forwardly and around the sprocket wheels 17 at the front will slide behind the shield 23 and in passing to the top of said sprocket 95 wheels will be free to swing upwardly and rearwardly to extended position. On account of the blades being buoyant, when they move to the top, the buoyancy will cause the blades to swing upwardly, tending 100 to float to the surface of the water, thereby automatically opening or moving the blades to a position to receive the force of the water flowing over the motor, for driving the motor, and when the blades are 105 110

carried down under the rear sprocket wheels 17, the buoyancy of the blades will swing them rearwardly and upwardly against the chains so as to move forwardly reverse to 5 the current, with minimum resistance.

The buoyancy of the blades, assisted by the buoyancy of the frame, if made of wood will enable the motor to be readily raised and lowered, and by raising the motor sufficiently so that the uppermost blades 10 extend partly out of the water, the power can be decreased.

A sprocket wheel 24 is secured to one end of the front shaft 15 and is connected by 15 an endless sprocket chain 25 with a sprocket wheel 26 secured to a power transmitting shaft 27 journaled on the corresponding pier 8, whereby the power is transmitted to the shaft 27. When the motor is raised, the 20 chain 25 is slackened, and the slack is taken up by an idler 28 carried by an adjustable arm 29 secured in a clamp 30. Said arm can be adjusted to different angles for positioning the idler 28 for holding the chain 25 25 taut.

Several of the motor units can be disposed side by side, and the adjacent ends of the shafts have coupling flanges 31 for attaching the shafts of companion units (not 30 shown) together.

It is also preferable to have a wall or submerged dam 32 between the front piers 8 to prevent the flow of water under the motor, and to compel the water to pass

over the motor, in order to prevent loss of 35 power.

Having thus described the invention, what is claimed as new is:—

A water motor comprising a pair of front piers, a pair of rear piers, a vertically 40 adjustable frame having its front and rear ends abutting the front and rear piers for vertical sliding motion, means carried by the piers and connected to the frame for adjusting the frame vertically, front and 45 rear transverse shafts carried by the frame, sprocket wheels on said shafts, endless sprocket chains passing around said sprocket wheels, a deck supported by the frame underneath the upper runs of the 50 chains for supporting the chains between wheels, a boxing carried by the frame below the deck and enclosing the lower portions of the chains and sprocket wheels, buoyant blades hingedly connected to said chains to swing away from and against the chains by the buoyancy of said blades at the upper and lower runs of the chains, and a submerged dam between the front piers to compel the water to flow over said deck 55 and frame.

In testimony whereof I have signed my name to this specification in the presence of two subscribing witnesses.

FRANK CHAPMAN.
